US00D778255S

(12) **United States Design Patent** (10) Patent No.: **US D778,255 S**
Brunner et al. (45) Date of Patent: ** Feb. 7, 2017

(54) **AUDIO LISTENING SYSTEM**(71) Applicant: **Apple Inc.**, Cupertino, CA (US)(72) Inventors: **Robert Brunner**, San Francisco, CA (US); **Gregoire Vandenbussche**, San Francisco, CA (US); **Christopher Fruhauf**, San Anselmo, CA (US)(73) Assignee: **APPLE INC.**, Cupertino, CA (US)(**) Term: **14 Years**(21) Appl. No.: **29/526,277**(22) Filed: **May 7, 2015****Related U.S. Application Data**

(60) Continuation of application No. 29/488,470, filed on Apr. 18, 2014, now Pat. No. Des. 729,198, which is a division of application No. 29/475,634, filed on Dec. 4, 2013, now Pat. No. Des. 704,163, which is a continuation of application No. 29/417,832, filed on Apr. 9, 2012, now Pat. No. Des. 696,226, which is a division of application No. 29/382,418, filed on Jan. 3, 2011, now Pat. No. Des. 657,345.

Primary Examiner — Paula Greene(74) *Attorney, Agent, or Firm* — Sterne, Kessler, Goldstein & Fox P.L.L.C.**CLAIM**

The ornamental design for an audio listening system, as shown and described.

DESCRIPTION

FIG. 1 is a front right perspective view of an audio listening system showing our new design;

FIG. 2 is a front view thereof;

FIG. 3 is a right side view thereof; and,

FIG. 4 is a bottom view thereof.

The broken lines in the figures show portions of the audio listening system that form no part of the claimed design.
